UNITED STATES PATENT OFFICE.

ALBERT WILTZ, OF ADDY, WASHINGTON.

FLUID-PUMP.

1,251,155.

Specification of Letters Patent. Patented Dec. 25, 1917.

Application filed April 10, 1917. Serial No. 160,947.

To all whom it may concern:

Be it known that I, ALBERT WILTZ, a citizen of the United States, residing at Addy, in the county of Stevens and State of Washington, have invented certain new and useful Improvements in Fluid-Pumps, of which the following is a specification.

This invention relates to new and useful improvements in fluid pumps and the principal object is to provide a device of this character which will facilitate the removal of fluid contents from barrels, shipping tanks, drums, etc.

A further object of the invention resides in providing a device whereby virtually the entire contents of such vessel may be removed by means of one operation.

A further object of the invention resides in providing a device wherein I am enabled by use of the same implement to provide for air-tight connection with tanks, drums or barrels provided with various sized openings for the removal of their liquid contents.

With these and numerous other objects in view my invention consists in the novel features of construction, combination and arrangement of parts as will be hereinafter referred to and more particularly pointed out in the specification and claims.

30 In the accompanying drawings forming a part of this application,

Figure 1 is a view of my pump partly in section.

Fig. 2 is a plan view thereof.

35 Fig. 3 is a partial view of the base.

Fig. 4 is a partial cross section through the base disclosing the valve closure means for preventing the escape of air from the vessel to which the pump is attached.

40 In describing my invention I shall refer to the drawings in which similar reference characters designate corresponding parts throughout the several views and in which 1 designates a base member provided to support

45 upstanding cylinders 2 in which are mounted pistons 3 provided with stems 4 slidably mounted in a guide bushing 5 which is a part of the handle supporting frame 6.

6 is designed to embody the cover plates 7 of the cylinders 2 and be secured thereto by means of bolts or screws 8. An upstanding arm 9, bifurcated and provided with openings 10, serves to support an operating beam 11 and a pin 10' serves for pivotal engagement within the bifurcated portion 9. The

beam 11 consists of an upstanding lever engaging stub 12 and out-spreading arms 13 and 14 each provided with curvilinear slots 15 and 16, respectively. Upon the ends of the piston rods 4 are eye-members 17 provided for pin connection to the beams 11 and being loosely connected to the slots 15 and 16 for operation therein.

Provided for engagement with the stub 12 is a handle member 18 provided with a hole 19 by which it may be disposed upon a nail or hook out of reach of mischievously inclined children. At 20 I provide the edges of the handle with beveled portions which are intended to engage with upstanding lugs 21 provided on the base 1. This provides a wrench engagement of the handle with the base and will be used in adjusting a pump to a fluid container. Upon the lower portion of the base are threaded bosses 22 and 23 of various sizes for engagement with the standard tanks or drums that are used in shipping liquids throughout the country and extending below the threaded boss 23 I provide a tapered threaded plug 24 provided for use upon wooden containers such as the usual type of barrel wherein it is necessary to fit the pump of my construction in the bung thereof and tightly engage it through means of the threads therewith to prevent a leakage of air therefrom.

In order to secure leverage for adjusting my pump in the various containers necessary, I make use of the handle as above described, and by this means secure sufficient leverage. In operation of the pump, it is desired, at times, to stop the flow and for this purpose I provide a winged plug 25 threadably secured in the base 1 and engaging with the passage extending therethrough. As the pump of my construction is designed to force air under pressure within the tank and by means of the pressure expel the liquid contents thereof, it will be evident that by unscrewing the plug 25 and neutralizing the pressure within the tank I am enabled to stop the flow. About centrally of the base member I provide a tubular passage 26 and upon the upper end thereof provide a supply hose 27 with a liquid-tight connection therewith. Upon the bottom and extended end of the tubular passage I mount a similar hose 28 of sufficient length to extend to the bottom of a drum or other container. In some types of containers the closure is in

the end and others in the sides, and it is necessary that I extend the hose connection 28 sufficiently to overcome the extreme conditions that have to be met. I provide a serrated end to the hose 28 so that it will not become closely engaged with the sides or bottom of the tank to prevent a flow of fluid therethrough when pressure has been placed in the tank.

- 10 10 After attaching the device of my construction to a liquid container by working the handle 18 I am enabled to pump a pressure of air upon the liquid contents to expel same through the hose 28 and through the passage 26 and hose 27 to the desired point of use. To insure against leakage of the air pressure when the pump is at rest I dispose in the air passage 29 a check valve 30 of the usual plunger type and prefer that this check 15 15 valve be similar to those in use in tire air tubes and the like so that replacement may be easily made.

From the foregoing it will be seen that I have provided a simple, inexpensive and efficient means for carrying out the objects of the invention, and while I have particularly described the elements best adapted to perform the functions set forth, it is obvious that various changes in form, proportion 20 20 and in the minor details of construction may be resorted to, without departing from the spirit or sacrificing any of the principles of the invention.

I claim:—

- 35 1. In a fluid pump, a combination with air pressure cylinders, of a supporting base therefor provided with means for attachment to barrels, drums or tanks having a variety of sized openings therein, a fluid outlet 40 40 through said base, connections therewith, one extending downward into the receptacle and one leading upward and to the point of

delivery, plungers in said cylinders, and operating means therefor.

2. In a fluid pump, the combination with air pressure cylinders, of a supporting base therefor provided with stepped threaded means for attachment to containers having various sizes of openings, a fluid outlet through said base, a hose connection extending into the barrel and another extending upward for engagement with a supply hose, plungers in said cylinders, and operating means therefor consisting of a beam with slotted engagement with the plungers and pivoted at its center, an upstanding handle engaging stub thereon and a handle fitting thereto, and said handle provided with means for engaging the base for securing said base to a container.

3. In a fluid pressure pump, the combination of air pressure cylinders, plungers therein, means for operating same, of a base fitted for attachment to various types of fluid containers, air passages leading from the cylinders and leading into the interior of the container, a check valve interposed therein to prevent back flow of air, flexible hose connection fitted to the under-side of the base and extending into the container, said means provided with a serrated end, and means on the upper side of the base for the attachment of a supply hose.

4. In a fluid pressure pump, the combination with air pressure cylinders and operating means therefor, of a base supporting said cylinders and provided with threaded means for engaging containers of various kinds and one of said means consisting of a threaded taper for adjusting said pump to a bung hole of a wooden barrel, and means for sealing it therewith.

In testimony whereof I affix my signature.
ALBERT WILTZ.
